UNITED STATES PATENT OFFICE.

PETER SHANNON, OF CHICAGO, ILLINOIS.

STREET-FLUSHING APPARATUS.

1,256,064.

Specification of Letters Patent.

Patented Feb. 12, 1918.

Application filed October 18, 1916. Serial No. 126,262.

To all whom it may concern:

Be it known that I, PETER SHANNON, a citizen of the United States of America, and a resident of Chicago, in the county of Cook, State of Illinois, have invented certain new and useful Improvements in Street-Flushing Apparatus, of which the following is a specification.

This invention relates to that class of street washing or flushing machines in which the liquid from a tank or other source of supply is forcibly discharged along the surface of the roadway to wash the dirt and impurities thereon toward the side gutters of the roadway.

And the present improvement has for its object to provide a simple and efficient structural formation and combination of parts, by means of which the discharge of fluid is controlled and directed, to evenly wash all portions of the roadway when required, and with which adjustment can be made to flush or wash a longitudinal portion of the roadway, to the exclusion of the other portion or portions thereof, all as will hereinafter more fully appear.

In the accompanying drawings:

Figure 1, is a plan view of the forward part of a motor-truck having the present invention applied.

Fig. 2, is an enlarged detail transverse section on line 2—2, Fig. 1.

Fig. 2^a, is a detail section on line 2^a—2^a, Fig. 2.

Fig. 2^b, is a perspective view of the connecting parts between the flushing nozzle and the forward axle of the motor truck, said parts being shown in a detached condition.

Fig. 3, is a fragmentary plan view of the mechanism shown in Fig. 2.

Fig. 4, is an enlarged detail plan view of the variable speed mechanism of the apparatus, the cover portion of the casing being removed.

Fig. 5, is a detail front elevation, with parts in section, illustrating the arrangement of the manually actuated controlling means of the apparatus.

Fig. 6, is a detail longitudinal section of the same, on line 6—6, Fig. 1.

Fig. 7, is a rear elevation of the same.

Fig. 8, is a transverse section of same on line 8—8, Fig. 6.

Similar reference numerals indicate like parts in the several views.

Referring to the drawings, 1 designates the front end of a motor-truck of any ordinary form, and upon which a fluid supply tank 3 is mounted, as usual in the present type of apparatus.

2 designates one of the intermediate springs by which the frame 1 is connected to the forward axle 2^a of the truck.

4 designates the driving motor or engine, 65 and 5 the power or driving shaft of the same. Said shaft has the usual driving connections with the rear wheels of the truck as well as the usual controlling accessories.

7, designates the power pump of the present apparatus, the inlet end of which is connected by a pipe section 9, with the supply tank 3 aforesaid.

10, designates a three-way valve arranged in the pipe section 9 aforesaid, and 11, a lateral branch pipe connected to said valve and adapted for connection with a suitable source of fluid supply from which the tank 3, is filled from time to time. The valve 10 is adapted to connect in a direct manner the 80 lateral branch pipe 11 with the tank 3, when it is desired to fill said tank from a source of fluid supply under pressure. The main function of said valve 10, however, is to connect said lateral branch pipe 11, with the 85 power pump 7 aforesaid, so that said pump may draw the liquid from said branch pipe 11, and force said liquid through the herein-after described heating means, and from thence into the tank 3.

12, designates the outlet pipe of the power pump 7, having a transversely disposed portion, adapted for connection with the roadway flushing means hereinafter described.

13, designates a heating device of any 95 usual and suitable form, associated with the outlet pipe 12, aforesaid, and adapted to heat the fluid passing through the same.

14, designates a three-way valve arranged in the outlet pipe 12 aforesaid, and 15 a lateral branch pipe connected to said valve and connected to the tank 3, aforesaid. Said valve 14 ordinarily closes communication between the outlet pipe 12 and lateral branch pipe 15 so that the flow of fluid from the 105 pump 7 will be directed wholly to the above mentioned roadway flushing means; said valve is adapted for adjustment so as to close communication with said roadway flushing means; and open communication between the 110 pump 7 and said branch pipe 15, when it is desired to heat the contents of the tank 3, by

a circulation of the fluid from the tank through the heating device 13 aforesaid, and back into said tank through said branch pipe 15.

- 5 16, designates a hollow head journaled transversely of the tank frame 1 and near the forward end of the same. At one end said head 16, is provided with a packing gland 17, adapted to receive the end of the transverse 10 portion of the outlet pipe 12 of the pump, and connect the parts so that independent rotation of the hollow head 16 may be effected without leakage of the fluid passing through the parts. At its other end said 15 hollow head 16, is provided with trunnion extensions upon and in which the operating parts hereinafter described are revolvably mounted.

18 designates a depending neck on the 20 lower side and midway the length of the hollow head 16, providing a bearing and a communicating connection for the upright attaching portion of the flushing nozzle of the apparatus.

25 The flushing nozzle above referred to is preferably formed by two telescoping sections 19 and 19' adjustably connected together by means hereinafter described, with the upper end of the upper section journaled 30 in the aforesaid depending neck 18 of the hollow head 16 as shown more particularly in Fig. 2.

The lower section 19' of the flushing nozzle is of an L shape, having a vertical portion 35 adapted for sliding movement in the upper section 19, and a horizontal outlet portion which in an assemblage of the mechanism is arranged adjacent to the surface of the roadway to discharge a stream of flushing fluid horizontally along said roadway. In the construction the sections 19, 19', are 40 connected together by adjusting bolts 19'' and maintained in an extended condition by an interposed spiral spring 19''' as shown in 45 Fig. 2.

The lower section 19' of the flushing nozzle is connected to the forward axle 2' so as 50 to be maintained in the same relation to the roadway as that of the ground wheels of said axle by means as follows:

20, 20 designate transverse bracket rails associated with the axle 2' and carrying at their adjacent ends guide piece 20' formed with segmental guide slots 20'' for guiding 55 engagement with the cross-head hereinafter described.

21 designates an L shaped bracket piece, the horizontal member of which is orificed for the passage of the vertical portion of the 60 lower nozzle section 19', and which section 19' is supported in place by a fixed flange on its periphery resting on top of said horizontal member as shown in Figs. 2 and 2a. The vertical member of the bracket piece 21 65 is formed with a vertical series of bolt holes

21' by which it is secured in a vertically adjustable manner to the cross-head now to be described.

22, 22 designate a cross head of a plate form with its respective ends formed with guide 70 lugs 22' for guiding engagement with the segmental guide slots 20'' above described. The construction is adapted to steady the flushing nozzle 19' and its accessories, and hold the same from vibration in actual use. 75 As heretofore mentioned the cross head 22, carries in a vertically adjustable manner the L shaped bracket member 21, above described.

23, designates a worm rim forming a fixed 80 part of the hollow head 16 aforesaid, and having operative engagement with a worm 24, the carrying shaft of which is adapted for manual actuation by connections hereinafter described in detail, to attain a turning 85 adjustment of the hollow head 16 and associated flushing nozzle 19, 19' to attain an adjustment of said parts in a vertical longitudinal plane.

25, designates a bevel gear ring forming a 90 fixed part of the upright portion 19 of the flushing nozzle aforesaid, and constituting the driven member of the mechanism hereinafter described in detail, and by which an oscillatory or rocking movement in a horizontal 95 plane is imparted to the said flushing nozzle.

26, designates a counter shaft associated with the power shaft 5 aforesaid, and receiving changeable speed of rotation therefrom 100 through an intermediate speed changing mechanism of any ordinary and suitable type. In the example shown in Figs. 1 and 4, the power shaft 5 carries a series of spur gears 27 of different diameters, keyed or 105 otherwise fixedly secured to said power shaft.

28, designates a series of spur gears mounted loosely on the countershaft 26, and meshing with and individual to the series of spur gears 27 of the power shaft 5.

29, designates a series of clutches individual to the series of spur gears 28, and adapted to clutch the same to the countershaft 26.

30, designates a clutch operating shaft 115 adapted for manual rotation, and provided with a series of cam disks 31, having operative connection with the aforesaid clutches 29. Said cam disks 31 are so arranged with relation to each other, that with one cam disk in position to clutch an individual gear 28 to the countershaft 26, the individual clutches of the remaining gears 28 will be inoperative positions, due to the arrangement of said cam disks 31.

Accordingly with a progressive turning movement of the clutch operating shaft 30, the cam disks 31 will be serially brought into action to attain the desired speed of rotation of the countershaft 26, and of the 130

pump 7, the driving shaft of which has chain and sprocket connection 32 with said countershaft 26, as illustrated in Figs 1 and 2. With the above described mechanism the speed of the pump 7 can be varied to suit the different requirements met in actual use.

33, designates a secondary countershaft associated with the power shaft 5, in manner similar to the countershaft 26, above described and receiving variable speed of rotation from said power shaft through an intermediate speed changing mechanism similar to that already described, and which in the construction illustrated in Figs. 1 and 2, comprises parts as follows:—

34, designates a series of spur gears loosely mounted on the countershaft 33 and individual to and meshing with the heretofore described series of spur gears 27, of the power shaft 5.

35, designates a series of clutches individual to the series of spur gears 34 and adapted to clutch the same to the countershaft 33.

36, designates a clutch operating shaft adapted for manual rotation and provided with a series of cam disks 37 operatively engaging the series of clutches 35 aforesaid. The arrangement of the cam disks 37 is similar to the series of cam disks 31 before described, so that with one cam disk 37 in position to clutch an individual gear 34 to the countershaft 33, the clutches of the other gear 34 will be inoperative positions, and so that with a progressive turning movement of the clutch operating shaft 36, the series of cam disks 37 will be serially brought into action to attain the desired speed of rotation of the secondary countershaft 33 above described.

In the preferred construction shown in Figs. 1 and 4 of the drawings, the inclosing casing for the speed changing mechanisms above described, is fixedly secured to and carried by the housing of the motor or engine 4 of the apparatus. The above described mechanism is intended to govern the speed of oscillation of the horizontal portion of the lower nozzle section 19' heretofore described, and in connection therewith additional intermediate mechanisms as follows are used.

38, designates a shaft, extending longitudinally of the main frame 1 and operatively connected near one end to the countershaft 33 aforesaid, by means of a chain and sprocket connections 39. At its other end said shaft 38 is operatively connected by a worm and worm gear connection 40 with a transversely arranged shaft 41, journaled in the main frame 1 and in the end of the hollow head 16 heretofore described.

42 designates a transversely arranged housing surrounding the shaft 41 afore-

said, and journaled thereon and on an end trunnion portion of the hollow head 16 aforesaid, so as to be capable of independent rotary adjustment for the purpose hereinafter stated.

43, designates a worm rim forming a fixed part of the housing 42 aforesaid, and having operative engagement with a worm 44, the carrying shaft of which is adapted for manual actuation by means hereinafter described in detail, to attain a turning adjustment of said housing 42. Such turning adjustment through the intermediate mechanism hereinafter described, being transmitted to the horizontal portion of the lower nozzle section 19' to effect a turning adjustment of the same in a horizontal plane, with the result that the horizontal portion of the section 19' will discharge more toward one side of the roadway than to the other side, and instead of centrally of the roadway in the normal position of the mechanism.

45, designates a saddle frame adapted for adjustment in a transverse direction in the housing 42 aforesaid, and having a journal bearing for the carrying shaft 46 of a bevel gear wheel 47, as shown in Fig. 2.

48, designates a collar slidably mounted on the shaft 46 aforesaid, and having link connection 49 with the saddle frame 45, to attain an adjustment of said saddle frame lengthwise of the shaft 46 and independent of the rotation of said shaft. The collar 48 is adapted for manual actuation by the means hereinafter described in detail, in the adjustment of the throw of the horizontal portion of the nozzle section 19' in a horizontal plane, heretofore described.

50, 51, designate companion unlubricated bevel gears having spline or like sliding connections with the shaft 41 aforesaid; said gears have operative engagement with opposite sides of the aforesaid bevel gear wheel 47, and their toothed portions are so positioned in relation to each other that they will have alternate operative engagement with the gear wheel 47, and impart thereto semi-rotary motion alternately in opposite directions, while said gears 50, 51 receive constant rotation from the shaft 41. In the present structure the bevel gears 50, 51 are held in operative relation to the gear wheel 47 by the horns of the saddle frame 45, as illustrated in Fig. 2.

52, designates a rock arm carried by the shaft 46 and having a rocking movement in unison with that of the bevel gear wheel 47 aforesaid.

53, designates a transversely arranged toothed sector arm, pivoted at one end to the housing 42, and formed with an elongated slot 54 for operative engagement with a crank pin on the free end of the aforesaid rock arm 52. And the arrangement is

such that as the rock arm 52 and its carrying accessories above described, are moved to and from the pivoted end of the sector arm 53, the throw of the same will be correspondingly increased or diminished with a corresponding increase or decrease in the horizontal throw or rocking motion of the horizontal portion of the lower nozzle section 19', with which said sector arm 53

5 has operative connection by means as follows:—

55, designates a bevel gear wheel journaled on a trunnion portion of the hollow head 16 aforesaid, and having operative engagement with the toothed end of the sector arm 53 aforesaid, and with the heretofore described bevel gear ring 25 of the upper tubular section 19 of the flushing nozzle to form the above mentioned intermediate connection of the parts. With the structure above described, the bevel gear wheel 55 has a turning shift in unison with the turning adjustment of the housing 42 as the same is manually adjusted in the attainment of the horizontal adjustment of the horizontal portion of the lower nozzle section 19' before described.

30 The manually actuated mechanisms, by which the various adjustments of the parts of apparatus, heretofore described, are attained comprise as follows:—

56, designates a box or housing arranged convenient to the seat of the operator and provided with bearings for the shafts of the series of individual hand levers 57, 58, 59, 60 and 61 of the mechanisms, as well as constituting an inclosure for the rear ends of the intermediate shafts now to be described.

62, 63, 64, 65 and 66 designate a series of 40 longitudinally arranged shafts, preferably of the tubular type shown, and arranged concentrically one within the other with their rear ends extending into the interior of the box or housing 56, and with the plurality of shafts 63, 64, 65 and 66 provided with individual sprocket wheels 67, 68, 69 and 70 for operative chain connections with a corresponding series of individual sprocket wheels 71, 72, 73 and 74 on the carrying shafts of the hand levers 58, 59, 60 and 61 aforesaid.

55 The rear end of the central shaft 62 aforesaid, is directly attached to its operating hand lever 57, while its forward end is operatively connected by a crank arm 75, link 76, lever 77 and link 78 with the sliding collar 48 heretofore described to effect the heretofore described change in the horizontal throw of the flushing nozzle 20.

60 The forward end of the tubular shaft 63, is provided with a sprocket wheel 79 for operative chain connection with a sprocket wheel 80 on the cam shaft 36 of the speed changing portion of the mechanism by

65 which the horizontal portion of the lower

nozzle section 19' is oscillated in a horizontal plane, as heretofore described.

The forward end of the tubular shaft 64 is provided with a sprocket wheel 81 for operative chain connection with a sprocket 70 wheel 82 of the shaft 30 of the speed changing portion of the mechanism of the pump 5 heretofore described in a horizontal plane, heretofore described.

The forward end of the tubular shaft 65 75 is provided with a sprocket wheel 83 for operative chain connection with a sprocket wheel 84 on the carrying shaft of the worm 44 by which a turning movement of the housing 42, to attain an adjustment of the 80 horizontal portion of the lower nozzle section 19' in a horizontal plane as heretofore described.

The forward end of the tubular shaft 66 is provided with a sprocket wheel 85 for operative chain connection with a sprocket wheel 86 on the carrying shaft of the worm 24, by which a turning movement of the hollow head 16 is effected, to attain the heretofore described swinging adjustment of the 90 horizontal portion of the lower nozzle section 19' in a vertical plane.

Having thus fully described my said invention, what I claim as new and desire to secure by Letters Patent, is:—

1. In a street flushing apparatus, the combination of a truck frame, an L shaped flushing nozzle having a vertical branch revolubly connected to said frame, a fluid supply pipe associated with said vertical branch, means for imparting continued oscillation to said flushing nozzle and means for varying the degree of the oscillations imparted to said nozzle during the oscillatory movement of the same, substantially as set forth.

2. In a street flushing apparatus, the combination of a truck frame, an L shaped flushing nozzle having a vertical branch revolubly connected to said frame, a fluid supply pipe associated with said vertical branch, means for imparting continued oscillation to said flushing nozzle, means for varying the degree of the oscillations imparted to said nozzle during the oscillatory movements of the same, and means for varying the speed of the oscillations imparted to said nozzle during the oscillatory movements of the same, substantially as set forth.

3. In a street flushing apparatus, the combination of a truck frame, a flushing nozzle comprising vertical and horizontal branches, the vertical branch being journaled on the truck frame for oscillatory movement of the horizontal branch in a horizontal plane, a fluid supply associated with said flushing nozzle, means for imparting continuous oscillation to said flushing nozzle, and manually actuated means for shifting laterally the zone of oscillation of the horizontal

branch of the flushing nozzle, substantially as set forth.

4. In a street flushing apparatus, the combination of a truck frame, an L shaped flushing nozzle having a vertical branch revolubly connected to said frame, a fluid supply pipe associated with said vertical branch, means for imparting continued oscillation to said flushing nozzle, means for shifting in a horizontal plane the zone of oscillation of said nozzle, and means for varying the degree of the oscillations imparted to said nozzle during the oscillatory movement of the same, substantially as set forth.

5. In a street flushing apparatus, the combination of a truck frame, a hollow head journaled transversely in said frame and provided with a lateral tubular extension, a fluid supply pipe provided with coupling for engagement with said tubular extension, means for imparting a turning adjustment to said tubular extension, and an L shaped flushing nozzle having a vertical branch revolubly associated with said hollow head, substantially as set forth.

6. In a street flushing apparatus, the combination of a truck frame, a forward axle, resilient means intermediate of said frame and axle, an L shape discharge nozzle, hav-

ing a vertical portion formed in two sections with the upper section connected to the truck frame and the lower section connected to the axle and means for supplying fluid to said discharge nozzle, substantially as set forth.

7. In a street flushing apparatus, the combination of a truck frame, a forward axle, resilient means intermediate of said frame and axle, an L shape discharge nozzle, having a vertical portion formed in two sections with the upper section connected to the truck frame and the lower section connected to the axle in a vertically adjustable manner, and means for supplying fluid to said discharge nozzle, substantially as set forth.

8. In a street flushing apparatus, the combination of a truck frame, a forward axle, resilient means intermediate of said frame and axle, an L shape discharge nozzle having a vertical portion formed in two sections with the upper section connected to the truck frame and the lower section connected to the axle by a cross-head, and a guide bracket associated with the axle and having a sliding connection with the aforesaid cross-head, substantially as set forth.

Signed at Chicago, Illinois, this 16th day of October, 1916.

PETER SHANNON.
